CLAIM

The ornamental design for a safe for storage of monetary bills, as shown and described.

DESCRIPTION

FIG. 1 is a front, top, right side perspective view of a safe for storage of monetary bills showing our new design; FIG. 2 is a front, top, left side perspective view thereof; FIG. 3 is a front, bottom, right side perspective view thereof; FIG. 4 is a front view thereof; FIG. 5 is a back view thereof; FIG. 6 is a top view thereof; FIG. 7 is a bottom view thereof; FIG. 8 is a left side view thereof; and, FIG. 9 is a right side view thereof.

(Continued)

The broken lines illustrating portions of the safe for storage of monetary bills form no part of the claimed design.

1 Claim, 9 Drawing Sheets
